(57) **CLAIM**

The ornamental design for a crown-shaped food product, as shown and described.

DESCRIPTION

FIG. 1 is a perspective view showing an embodiment of my new design, comprising a crown-shaped food product; FIG. 2 is a front elevation view of the crown-shaped food product of FIG. 1, the back elevation view being identical thereto;

FIG. 3 is a right side elevation view of the crown-shaped food product of FIG. 1, the left side elevation view being identical thereto;

FIG. 4 is a top plan view of the crown-shaped food product of FIG. 1; and,

FIG. 5 is a bottom plan view of the crown-shaped food product of FIG. 1.
